US00D991116S

(12) **United States Design Patent** (10) Patent No.: **US D991,116 S**
(45) Date of Patent: **** Jul. 4, 2023**

(54) **GEAR SHIFT LEVER**

(71) Applicant: **Mengke Ling**, Guangzhou (CN)

(72) Inventor: **Mengke Ling**, Guangzhou (CN)

(**) Term: **15 Years**

(21) Appl. No.: **29/881,789**

(22) Filed: **Jan. 6, 2023**

(51) LOC (14) Cl. **12-03**

(52) U.S. Cl.

USPC **D12/179**

(58) **Field of Classification Search**

(57) **CLAIM**

The ornamental design for a gear shift lever, as shown and described.

DESCRIPTION

FIG. 1 is a rear, right and top perspective view of a gear shift lever, showing my new design;

FIG. 2 is a front, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the gear shift lever that form no part of the claimed design.

1 Claim, 8 Drawing Sheets

EX PARTE
REEXAMINATION CERTIFICATE

THE PATENT IS HEREBY AMENDED AS 5
INDICATED BELOW.

AS A RESULT OF REEXAMINATION, IT HAS BEEN
DETERMINED THAT:

The claim 1 is cancelled. 10
